UNITED STATES PATENT OFFICE

171,496

FENDER FLAP

Michael Hallward, Swampscott, Mass., assignor
to Signal Manufacturing Co., Lynn, Mass., a
corporation of Massachusetts

Application September 11, 1953, Serial No. 26,771

Term of patent 14 years

(Cl. D14—6)

To all whom it may concern:

Be it known that I, Michael Hallward, a citizen of the United States, residing at Swampscott, in the county of Essex and State of Massachusetts, have invented a new, original, and ornamental Design for a Fender Flap, of which the following is a specification, reference being had to the accompanying drawing, forming a part thereof.

In the drawing:

Fig. 1 is a front view of the fender flap embodying my new design;

Fig. 2 is a cross-section taken along line 2—2 of Fig. 1;

Fig. 3 is a cross-section taken along line 3—3 of Fig. 1.

I claim:

The ornamental design for a fender flap, substantially as shown.

MICHAEL HALLWARD.
